UNITED STATES PATENT OFFICE

WILLIAM A. WULLE, OF CHICAGO, ILLINOIS, ASSIGNOR TO THE PYLE NATIONAL COMPANY, OF CHICAGO, ILLINOIS, A CORPORATION OF NEW JERSEY

AVIGATION LIGHT

Application filed April 7, 1930. Serial No. 442,064.

My invention relates to improvements in avigation lights for airships and the like and has for one object to provide a new and improved type of riding lights primarily for airplane use. One object of my invention is to provide a durable, easily assembled structure which will offer a minimum of wind resistance. Other objects will appear from time to time throughout the specification and claims.

10 My invention is illustrated more or less diagrammatically in the accompanying drawings, wherein—

Figure 1 is a side elevation;

15 Figure 2 is a section along the line 2—2 of Figure 1;

Figure 3 is a front elevation in part section;

20 Figure 4 is a detail of the lamp supporting frame;

Figure 5 is a perspective view of the exterior main frame;

Figure 6 is a section along the line 6—6 of Figure 5;

25 Figure 7 is an end elevation of the exterior sub-frame.

Like parts are indicated by like characters throughout the specification and drawings.

26 A is the exterior main frame. It is streamlined as indicated and terminates at each end in a boss A¹ A² apertured for holding screws. A³ is a supporting base or platform tied to the main frame A by the leg A⁴. This main frame is thicker at the top than at the bottom as especially indicated in Figures 3 and 6, having one side perpendicular to the plane of the base. This side being flanged about its entire periphery as at A⁵. A⁶ is the exterior sub-frame similar in side elevation to the upper portion of the frame

35 A but wider at the top than at the bottom so as to be complementary to the frame A. This sub-frame is interiorly flanged as at A⁷ so that when frames A and A⁶ are held together by the screws A⁸ they form an interiorly slotted holding and supporting member.

40 B is the lamp frame. It conforms in shape in general to the interior conformation of the combined frames A and A⁶. It is adapted to fit into them and to be held in position by

them. This frame B carries a bracket B¹ in which is mounted an electric lamp base B² carrying a lamp B³. The frame B is upwardly bent at the bottom as indicated at B⁴ to provide clearance for the conductors B⁵ which pass down through the hollow interior B⁶ of the base A³.

55 C C¹ are translucent half-globe sections peripherally flanged at C² to penetrate between and be locked in place by the frame members A and A⁶, the arrangement being as indicated in Figure 2 where the central lamp frame B and the flanges C² are held together in the channel formed by the flanges A⁵ A⁷. These translucent globes may be 60 painted or marked or colored in any desired manner depending upon the use to which they are placed, their position, the signals given by them and the like. Normally, for instance, the area X—X¹—X² will be blacked out. The area X—Y—Y¹ would be for instance red or green and the area Y¹—Y—X² would be 65 white though any desired combination of colors may be used or a uniform color or even an absence of color may be characteristic of the structure.

70 I claim:

1. An avigation light comprising a main frame, a supporting base upon which it is mounted, one side of the frame being perpendicular to the plane of the base, the other side being slightly inclined to the perpendicular side.

75 2. An avigation light comprising a main frame, a supporting base upon which it is mounted, one side of the frame being perpendicular to the plane of the base, the other side being slightly inclined to the perpendicular side, the frame on the perpendicular side being 80 interiorly flanged.

85 3. An avigation light comprising a main frame, a supporting base upon which it is mounted, one side of the frame being perpendicular to the plane of the base, the other side being slightly inclined to the perpendicular side, a sub-frame, means for mounting it on the main frame, the sub-frame having 90 one side perpendicular to the plane of the base, the other side inclined thereto in opposition to the inclined surface of the main 95

frame, means for removably fastening the two frames together.

4. An avigation light comprising a main frame, a supporting base upon which it is mounted, one side of the frame being perpendicular to the plane of the base, the other side being slightly inclined to the perpendicular side, a sub-frame, means for mounting it on the main frame, the sub-frame having one side perpendicular to the plane of the base, the other side inclined thereto in opposition to the inclined surface of the main frame, means for removably fastening the two frames together, both frames on their perpendicular side being interiorly flanged to form an interior peripheral channel.

5. An avigation light comprising an open interiorly channeled frame and a sub-frame removably mounted within the channeled periphery of the main frame, a light source mounted in the sub-frame.

6. An avigation light comprising an open interiorly channeled frame and a sub-frame removably mounted within the channeled periphery of the main frame, a light source mounted in the sub-frame, a cover plate peripherally flanged to conform to the inner contour of the main frame, the flange being adapted to rest in juxtaposition to the inner frame within the channel.

7. An avigation light comprising an open interiorly channeled frame and a sub-frame removably mounted within the channeled periphery of the main frame, a light source mounted in the sub-frame, a cover plate peripherally flanged to conform to the inner contour of the main frame, the flange being adapted to rest in juxtaposition to the inner frame within the channel, there being such a cover plate on each side of the inner frame.

8. An avigation light comprising a supporting base, an open frame projecting therefrom flanged at one side, a sub-frame removably mounted on the open frame, conforming in cross sectional area therewith, flanged on the side opposed to the main frame to form with the flange on the main frame a channel, an interior frame whose periphery engages within said channel, and a light source mounted on such frame.

9. An avigation light comprising a supporting base, an open frame projecting therefrom flanged at one side, a sub-frame removably mounted on the open frame, conforming in cross sectional area therewith, flange on the side opposed to the main frame to form with the flange on the main frame a channel, an interior frame whose periphery engages within said channel, a light source mounted on such frame, a translucent cover plate located on either side of the interior frame flanged to penetrate the channel between the interior frame and the flanges on the exterior frame.

10. An avigation light comprising a main

frame flanged at one side, a hollow base upon which it is mounted, an auxiliary frame flanged in opposition to the flanged side of the main frame to form with the flange on the main frame an inner peripheral channel, a lamp frame, its exterior conformation conforming to the contour of the bottom of the channel, a light source mounted on the light frame, curved cover panels one on each side of the light frame, flanged to be held between the flanges on the main frame whereby the flanges on the cover plates and the outer periphery of the lamp frame are held together in the main frame.

Signed at Chicago, county of Cook, and State of Illinois, this 31st day of March, 1930.

WILLIAM A. WULLE.
